UNITED STATES PATENT OFFICE.

STEPHEN VIRAGH, OF SWISSVALE, PENNSYLVANIA.

PIVOTED WINDOW.

1,115,753.

Specification of Letters Patent.

Patented Nov. 3, 1914.

Application filed November 1, 1913. Serial No. 798,722.

To all whom it may concern:

Be it known that I, STEPHEN VIRAGH, a resident of Swissvale, in the county of Allegheny and State of Pennsylvania, have invented a new and useful Improvement in Pivoted Windows, of which the following is a specification.

This invention relates to sliding and swinging sash windows, and particularly to windows embodying a sash rotatably connected to runner members which slide in grooves or runways in the pulley stiles.

The object of the invention is to provide a sliding and swinging sash window, having interlocking parts on the sash and runners extending from top to bottom thereof and thereby entirely preventing the entrance of air or moisture through the sash, wherein the hinge parts are almost entirely concealed between the sash and runners, but are nevertheless arranged so as not to interfere with the air tightening or interlocking members, and wherein the sliding runner and sash stile are locked together by the interlocking parts provided thereon and by the hinge leaves so that warping or loosening of the parts is prevented.

The invention comprises the construction and arrangement of parts hereinafter described and claimed.

In the drawings Figure 1 represents a front elevation of the lower portion of a window and frame embodying the invention; Fig. 2 is a side elevation of the sash, as the same appears viewed from the left, Fig. 1, and showing the sash in full lines at the beginning of its reversing movement, and in dotted lines near the end of said movement; Fig. 3 is a cross section on the line 3—3, Fig. 1, on an enlarged scale, looking in the direction of the arrows; Fig. 4 is a cross section on the line 4—4, Fig. 1, looking in the direction of the arrows; Fig. 5 is a detail side elevation, on an enlarged scale, of a special form of hinge; Fig. 6 is a plan or edge view of the hinge; and Fig. 7 is a perspective view of one of the runners.

The sash shown in the drawings comprises a top rail 1, bottom rail 2, and two vertical side members, each of which comprises a stile 6, and an extra member or runner 7, which travels along the runways 3 of the pulley stiles 4, which may be of any suitable construction. The stile and runner are provided with interlocking portions to secure a close fit therebetween and prevent

the entrance of air or moisture from the outside of the window. In the form shown in the drawings, the runners 7 are provided with longitudinal ribs 8, and the stiles with ribs 9, disposed oppositely to ribs 8. Ribs 8 and 9 extend vertically for the full length of the runner and stile, and are undercut or otherwise formed on an incline, as at 13^a. They may be either integral with, or secured to the stile 6 and runner 7 as desired. To interlock or match with the ribs 8 or 9, the stile 6 and runner 7 are respectively provided with ribs 10^a and 10, as shown in Figs. 3, 4 and 7. Rib 10^a is suitably secured to the upper half of stile 6 and is exactly half the length thereof. Rib 10 is of the same shape in cross section as rib 10^a and is of the same length, that is, half the height of the sash, and is secured to the lower half of the runner. The two ribs 10 and 10^a also abut end to end exactly midway of the height of the sash.

Stile 6 and runner 7 are hinged together, the hinges each comprising two leaves 11, 80 consisting of flat metal plates and lying in planes parallel to each other and slightly offset from each other. Said leaves have end edges 13^b and bottom edges 13, the latter being partly straight and partly curved, as at 13^a, on the arc of a circle, and extending up to the front face of edge 12 of the leaf. At one end each leaf is provided with a lug or ear 14, said lugs or ears being provided with apertures 15 to receive a suitable pin 16 whose axis is normal to the planes of the hinge leaves. In the form shown, pin 16 consists of a bolt having a slotted head 17, its opposite end being threaded to receive a nut 18. Both of the leaves 11 are provided with one or more suitably spaced apertures 19 for securing them to the window parts, as hereinafter described.

Rib 10 on the stile 6 is cut away or mortised on its face next to the stile to form a 100 socket 20. This socket may be formed by a rotating cutter, and consequently by a machine operation. It is preferably shaped with a partly straight and partly circular bottom corresponding to the shape of the hinge leaves 11. Rib 10^a is likewise provided with a socket 21, having a partly straight and partly circular bottom and mortised out of said rib on that side next to the runner.

Sockets 20 and 21 are provided to receive the two hinge leaves 11, and the latter are

secured, one to the stile 6, and the other to the runner 7, by screws 22 passing through the screw-holes 19. If desired, the ribs 10 and 10^a may be provided with apertures 23, 5 opposite holes 19, so that the hinge leaves may be secured to the runner and stile after the ribs 10 and 10^a have been secured thereto.

When the window is closed, as in full lines Fig. 2, the two hinge leaves 11 lie 10 wholly on opposite sides of the pivot, that hinge leaf which is secured to the stile 6 being above the pivot, and that which is secured to runner 7 being below the pivot. The end edges 13^b of the leaves lie in a common plane normal to the length of the stile and runner through the hinge axis. When 15 the window is rotated to open position, as shown in dotted lines Fig. 2, no parts of the hinge leaves project from the ribs 10 or 10^a. Moreover, the hinge leaves are 20 buried in said ribs and are therefore concealed, the only exposed parts being the pivot lugs and the edges of the leaves. The construction is therefore pleasing to the eye 25 and also is more durable as the hinge parts are protected from corrosion and rust. Again, each hinge leaf is arranged to fit its 30 socket snugly so that it is more securely and immovably attached than if merely screwed to the face of the stile or runner. Further, the construction does not break the continuity of the interlocking parts which extend unbroken the whole length of the sash, nor does it interfere with the abutment of 35 the ribs 10, 10^a at the middle of the sash. In the whole length of the interlocking

joint between sash stile and runner there is no portion mortised or cut away for the hinges or any other parts, to form points of leakage for air and dust to enter as in prior 40 pivoted sash windows.

What I claim is:

1. In a sliding and swinging sash window, a sash having side members each comprising a stile and a runner, said stile and 45 runner being each provided with a mortise, said mortises being offset from each other transversely to the length of the stile, the stile and runner each having a portion overlying the side of its respective mortise, and 50 a hinge having two leaves offset from each other and secured in said mortises.

2. In a sliding and swinging sash window, a sash having side members each comprising a stile and a runner, said stile and 55 runner being each provided with a mortise, said mortises opening outwardly only from the face of the sash and being offset from each other both longitudinally and transversely to the length of the stile, the stile 60 and runner each having a portion overlying the side of its respective mortise, and a hinge having two leaves offset from each other longitudinally of the hinge pintle and extending in opposite directions from said 65 pintle and secured in said mortises.

In testimony whereof, I have hereunto set my hand.

STEPHEN VIRAGH.
